UNITED STATES PATENT OFFICE.

EZRA P. KOONTZ, OF LIGONIER, INDIANA.

REFRIGERATOR.

SPECIFICATION forming part of Letters Patent No. 430,963, dated June 24, 1890.

Application filed September 1, 1888. Serial No. 284,364. (No model.)

To all whom it may concern:

Be it known that I, EZRA P. KOONTZ, a citizen of the United States, residing at Ligonier, in the county of Noble, State of Indiana, have invented certain new and useful Improvements in Refrigerators, of which the following is so full, clear, and exact a description as will enable others skilled in the art to which my invention belongs to make and use the same, reference being had to the accompanying drawings, in which—

Figure 1 is a front view of my refrigerator with the front removed and part of the two water-tanks broken away. Fig. 2 is a transverse vertical section on the line $x-x$ of Fig. 1. Fig. 3 is a transverse section of a refrigerator provided with but two tanks.

The object of my invention is to provide a refrigerator which shall combine extensive cooling powers for a given amount of ice with a portable structure.

To this end I construct my refrigerator with a double casing, as shown in the drawings, in which A is the exterior casing provided with perforations at the bottom. (Shown at a' .) Within this outer casing is situated an inner casing so placed as to leave a space C under and all around the inner casing between it and the outer casing. This space C has a free opening all around at the top when my refrigerator is covered. I secure complete circulation over as well as under and around my inner compartment by the following means:

The top or cover of my refrigerator is constructed as shown complete in Fig. 1, and in transverse section in Figs. 2 and 3. To the top piece A', which entirely covers my refrigerator, closing the air-space C, is attached the under piece B', which fits into and tightly closes the inner compartment inclosed by the casing B. Between these two parts of the cover I leave a space C', communicating with the air-space C by means of the three apertures b at the sides and back of the top. It will be readily seen that by this arrangement the air will have free circulation entirely around the inner compartment, both in the vertical and horizontal planes, as is shown by the arrows a.

Within the inner compartment D, I secure

transverse supports S, which serve to keep in place the ice and water tanks E, F, and G, as well as the provision-trays M.

As can be seen in the drawings, my refrigerator is provided with a plurality of tanks placed one above the other. In my preferred construction three tanks are shown, of which the top tank E holds the ice. The tank next below it F is for the storing of water for drinking purposes, and the bottom tank G holds the waste water from the melting ice in the tank E.

t is a perforated tray used to keep the ice off the bottom of the tank E. Two pipes J and I lead from the bottom of the ice-tank E. The longer pipe I extends past the back of the drinking-water tank F, as shown in Fig. 2, to a point directly above the waste-water tank G. The shorter pipe J leads directly into the drinking-water tank, and the flow of water from the melting ice into the tank F keeps the water therein constantly cold. A pipe K leads from a point near the top of the tank F into the tank G and serves as an overflow to the tank F. A similar pipe is attached to the tank G, as shown at L, and serves a similar purpose for said tank G. This pipe L is shown in the drawings as situated directly beneath the pipe I; but it is evident that it may be prolonged upward and connect with the pipe I, as shown in Fig. 3, thus forming a continuous pipe, the tank G being entirely dispensed with without departing from the spirit of my invention. It is also clear that the tank F may be used as a supplementary ice-tank, instead of a water-cooler, or that all three tanks may be placed in any part of the compartment D without materially departing from the spirit of my invention.

At c , c' , and c'' are shown perforations at the top and bottom, respectively, of the inner casing D, which provide means of communication between the inner compartment D and the air-space C. These perforations are not, of course, limited as regards size and number.

Supposing now the tank E to have been filled with ice and the tank F filled with water up to a proper level, the cooling of the air directly around tank E will set up a current throughout the whole refrigerator, which will follow a path conforming more or less to the

general directions indicated by the arrow *a* in Fig. 1. This cold air being heavier than the warmer air will take a downward course along that side of the refrigerator upon which the tanks are situated. This will necessitate an upward course of the warmer air upon the other side, and as more air is cooled it will drive out the warmer air through the apertures *c'* and into the air-space *C*. The cooler 5 part of the current having made its exit through the apertures *c* near the bottom of the refrigerator, will take a downward course and sink through the apertures *a'* in the bottom of the outer casing. The warmer 10 portions of the current will pass out through the perforations *c'* and tend to ascend through the air-passage *C* and to cross the top of the refrigerator through the perforations *b* and into that side of the air-space next the ice 15 and watertanks. The walls being naturally at a lower temperature at this point of the refrigerator, will cool the air as it rises at this point and facilitate its downward movement, thus completing the circuit to the apertures 20 *a'* at the bottom of the outer casing.

It is evident that a great advantage is gained by the provision of a waste-water tank within the refrigerator and directly in the line of downward movement of the cooling-air. Both this waste-water tank and the drinking-water tank being filled with water at practically the same temperature as the ice itself provide three times as great cooling-surface for a given quantity of ice without 25 the disadvantage of being obliged to spread this ice over a greater space. In the ordinary forms of refrigerators the cooling properties of the drip from the ice are lost, inasmuch as it is generally led away directly into 30 the sewer or is caught in a vessel placed beneath the refrigerator. To facilitate the formation of this cold-air current, perforations may be provided upon that side of the ice-tank next the provision-trays *M*; but these 35 perforations not being absolutely necessary are not shown herein.

It will often be advantageous to use the tank *F* for holding beverages other than water, such as milk, buttermilk, or cider. 40 For this purpose it would of course be inconvenient to allow the tank *E* to overflow into the tank *F*, as the water would dilute whatever liquid was being stored in the tank below. In such a case, then, a stopper should 45 be used, which stopper I have provided, as shown at *J'*. The most convenient form of stopper would of course be a cock, but a cork

will serve the purpose just as well; and I have shown both forms in the drawings. (See Fig. 2.) This stopper will also prove of advantage in the winter-time, when, although ice may be desired to preserve provisions, it is not found pleasant to drink ice-water.

I do not desire to be understood as limiting myself to the exact construction shown and described hereinabove, as many of the minor details may be altered without materially departing from the spirit of my invention. For instance, the waste-tank might be dispensed with, or the tank *F* might be used as a supplementary ice-tank, or all the tanks might be placed in the center of my ice-box with a provision-chamber on each side of them, or the whole interior construction in any of its various modifications might be situated within an ordinary single case; and all of these changes would not materially depart from the spirit of my invention.

Having now described the objects, uses, and advantages of my device, and having set forth a preferred method of construction, what I believe to be new and desire to secure by Letters Patent, and what I therefore claim, is—

1. In a refrigerator, an inner compartment 85 containing an ice-tank, drinking-water tank, and waste-water tank, in combination with a pipe leading from the bottom of the ice-tank to the waste-water tank, a pipe leading from the bottom of the ice-tank to the drinking-water tank, an overflow-pipe extending from the drinking to the waste water tank, and an overflow-pipe leading out of the waste-water tank, all substantially as and for the purposes herein set forth. 90

2. In a refrigerator, a plurality of tanks, one of which is designed to contain ice, and is located immediately above another which is designed to contain drinking-water, milk, or other fluids, in combination with a pipe connecting said tanks, means, substantially as described, for closing said pipe when the under tank contains a fluid other than water, and means, substantially as described, at the opposite side of said ice-tank extending therefrom to a point outside the refrigerator, serving to carry off the waste water. 95

In testimony whereof I affix my signature in the presence of two witnesses.

EZRA P. KOONTZ.
